UNITED STATES PATENT OFFICE.

AUGUST JAEGER, SR., OF GRAND RAPIDS, MICHIGAN.

SLIDING DOOR.

1,354,562.

Specification of Letters Patent.

Patented Oct. 5, 1920.

Application filed September 6, 1919. Serial No. 322,192.

To all whom it may concern:

Be it known that I, AUGUST JAEGER, Sr., a citizen of the United States, residing at Grand Rapids, in the county of Kent and 5 State of Michigan, have invented certain new and useful Improvements in Sliding Doors, of which the following is a specification.

My invention relates to hangings for sliding doors, and especially for sliding car doors for use upon freight cars, and its objects are: first, to provide a means whereby the door may be easily slid and without undue friction; second, to so arrange the 10 antifriction elements of my invention that they may be utilized to hold the door permanently in place when opened or closed, and, third, to provide a means whereby the antifriction elements may be brought into effective use without great effort on the part of the operator.

I attain these objects by the mechanism and arrangement of parts shown in the accompanying drawing, in which—Figure 1 is an elevation of a part of one side of a freight car with the door in place and the antifriction elements in anchored position. Fig. 2 is a sectional end view of the car door showing the manner of hanging the 15 same, and, Fig. 3 is a strip taken from the bottom of the door and having parts cut away to show the positions of the antifriction elements, or wheels, and how a spring may be applied to ease the movement of the 20 wheels from their anchored positions to the upper edge of the supporting rail without too great effort on the part of the operator.

Similar reference numerals indicate similar parts throughout the several views.

In the hanging of this door my first act is to provide supporting rails, 4, for the upper end of the door. To prevent the door from moving sidewise out of position I place an auxiliary rail 4' opposite the rail 5 4 and then form a groove 8 into each side of the door, with a cap 5 in position to be made to rest upon the rail 4 when the door is in its anchored positions.

The antifriction elements consists of 0 wheels 6 revolvably mounted in the lower edge of the door, and flanged, as shown in Fig. 2, so that when being run over the rail 2 the lower edge of the door will be held securely against lateral movement. It will 5 be readily understood that the rails 2 and 4 may be applied to hold the door closely

against the side of the car, or may hold the door away from the car, as desired.

The rail 2 is provided with several depressions, as indicated at 7, into which the 60 wheels are to drop when the door is either in opened position, or in closed position, as indicated by its solid lines, and by its dotted lines 3', respectively in Fig. 1. There may be three, or four of these depressions, or 65 even more, if desired, according to the length of the door.

In Fig. 3 I have shown how a spring 9 may be applied for the purposes: first, of avoiding a heavy shock upon the wheels 6 70 when they drop into the depressions 7, and, second, to partly support the door when in anchored position, and at the same time to assist in raising the door sufficiently to carry the wheels upon the highest plane of the 75 rail 2, for traveling over the rail to open or close the door, as indicated by the dotted lines 3'', in Fig. 1.

The spring 9 is designed to support none of the weight of the door except when the 80 wheels 6 have passed into the depressions 7 in the lower track. The neck 8 at the top of the door must be long enough to allow of all necessary raising and lowering of the door as the wheels 6 pass out of the 85 depressions and travel along upon the track. The cross head 5 above the neck 8 is designed to rest upon the upper bearings or tracks 4-4' when the wheels are in the depressions, as indicated at 3' and 5' in Fig. 90 1 and, in connection with the support of the spring 9, to support the entire weight of the door and relieve the weight from the wheels and their bearings.

The tracks 4-4' and 2 should be so located that the door cannot possibly come in contact with the wall 1 when opening and closing the door.

What I claim as new in the art, is:

1. In combination with a sliding door, a 100 single track below the door having depressions therein, wheels revolvably mounted in the lower end of the door to travel on the lower track, and engage the depressions therein, and two parallel tracks at the upper 105 end of the door, forming a slot between them, a cross head at the upper end of the door arranged to form a slim neck between the cross head and the body of the door, said cross head so adjusted that it will 110 move clear of the tracks when sliding the door and will rest upon the tracks when

the wheels are in the depressions in the lower track.

2. In combination with a sliding door, a single track below the door, said track having depressions at given points therein, wheels revolvably mounted in the lower edge of the door and fitted to travel upon the edge of the track and support the door when sliding it open or closed, and to enter said 10 depressions when in proper position therefore, a cross head at the upper end of the door having a thin slim neck, said cross head arranged to move freely with the door when sliding the door, two parallel tracks

at the upper end of the door forming a slot 15 for the free passage of the neck, the door so adjusted that the cross head will rest upon the upper tracks when the wheels are in the depressions in the lower track, and springs in the lower edge of the door 20 arranged to contact the lower track and ease the door in its downward movement as the wheels enter the depressions in the lower track.

Signed at Grand Rapids, Michigan, Sep- 25
tember 1, 1919.

AUGUST JAEGER, Sr.
